DESIGN.

M. H. SLATER.

TAPE MEASURE HOLDER AND PIN CUSHION.

APPLICATION FILED SEPT. 22, 1916.

50,083.

Patented Dec. 19, 1916.

Inventor:

Mark H. Slater

By her attorney, Charles S. Goodwin.

UNITED STATES PATENT OFFICE.

MABEL H. SLATER, OF WEBSTER, MASSACHUSETTS.

DESIGN FOR A TAPE-MEASURE HOLDER AND PINCUSHION.

50,083.

Specification for Design.

Patented Dec. 19, 1916.

Application filed September 22, 1916. Serial No. 121,677. Term of patent 14 years.

To all whom it may concern:

Be it known that I, MABEL H. SLATER, a citizen of the United States, residing at Webster, in the county of Worcester and State of Massachusetts, have invented a certain new, original, and ornamental Design for a Tape-Measure Holder and Pincushion, of which the following is a specification, reference being had to the accompanying drawing, forming part thereof.

The figure is a front elevation of a tape measure holder and pincushion, showing my new design.

Copies of this patent may be obtained for five cents each, by addressing the "Commissioner of Patents, Washington, D. C."

I claim—

The ornamental design for a tape measure holder and pin cushion, as shown.

In testimony whereof I have hereunto set my hand in presence of two subscribing witnesses.

MABEL H. SLATER.

Witnesses:

JOHN W. BURGEN,
HENRY F. ELDRIDGE.
